Delaware

Application November 12, 1934, Serial No. 752,636

17 Claims. (Cl. 204—9)

This invention relates to an electrolysis cell construction and the process of electrolysis carried out in that electrolysis cell. More specifically our invention relates to the preparation of persulfuric acid and persulfates, and materials derived therefrom, such as hydrogen peroxide, by electrolysis. More particularly the invention disclosed in this application is concerned with an improved construction for an electrolysis cell designed particularly for the preparation of the products above enumerated whereby these compounds may be produced more efficiently and more cheaply than heretofore possible.

One of the objects of this invention is therefore the development of an electrolysis cell and an electrolysis process for the preparation of persulfuric acid and persulfates electrolytically which will operate at a higher electrical efficiency than is usual with the electrolysis cells now in ordinary commercial usage. Another object of our invention resides in so arranging the different elements comprising our electrolysis cell that mechanical and/or chemical losses now incident to the production of persulfuric acid and persulfates by electrolysis may be reduced to a substantial degree. Still another and more specific object of our invention resides in preventing loss of the liquid containing persulfuric acid or a persulfate, which has been prepared by electrolysis, as a result of diffusion losses through the porous diaphragm which is usually an element of such electrolysis cells and separates the chamber containing the anode liquid or anolyte from the chamber containing the cathode liquid or catholyte. These and other objects of our invention, which will be obvious from the ensuing description, result in an improved electrolysis cell and an improved method of producing persulfuric acid, persulfates, and other similar chemicals by electrolytic action. The novel process resulting from the employment in electrochemical manufacturing of our novel electrolysis cell prepares the desired percompounds at higher electrical, chemical and mechanical efficiencies than are attainable in present day commercial operations.

Persulfuric acid is now commercially prepared by the electrolysis of an aqueous solution of sulfuric acid in an electrolysis cell having a platinum anode immersed in the anolyte (or liquid surrounding the anode) and a lead cathode in the catholyte (or liquid surrounding the cathode). When it is desired to prepare a persulfate salt electrolytically the same type of cell is utilized employing in lieu of the sulfuric acid usually an alkali metal sulfate or an acidulated solution of

ammonium sulfate. These cells contain a porous diaphragm which divides the space within the cell into two chambers, one containing the anolyte and the other containing the catholyte. It has been customary to form the porous diaphragm as a cylinder closed at the bottom, the space within the cylinder containing the anode and the anode assembly. The space external to the porous diaphragm contains the catholyte and the cathode, which may be made of lead bent in the form of a coiled tube which encircles the porous diaphragm. This lead tube ordinarily functions both as cathode and as a means through which the cooling water may be circulated for the purpose of cooling the catholyte.

Since it has not been possible in economical operation to produce persulfuric acid or persulfates in high concentrations in a single cell where in the electrolysis is carried out in a large volume of liquid, it is now customary in commercial practice to arrange a number of electrolysis cells in a cascade arrangement. Ordinarily such cells are arranged in banks each bank comprising an assembly of many anodes and anolyte liquors surrounded by a single catholyte and cathode assembly. Accordingly both the anolyte and the catholyte are permitted to flow from one cell of the cascade arrangement after electrolysis into a lower cell in the cascade arrangement where the liquids are again subjected to electrolysis thereby increasing the total overall concentration of persulfuric acid or persulfate in the anolyte. The concentration of persulfuric acid or persulfate is built up in the anolyte and it is this liquor in which we are interested because of its subsequent distillation and hydrolysis to yield vapors of hydrogen peroxide.

By thus circulating the cathode and anode liquids and permitting them to flow from cell to cell down through the bank, the cells being arranged in cascade, it has been possible to obtain ultimately in the final cell of the bank a liquid rich enough in persulfuric acid or persulfate to permit economical subsequent treatment to yield hydrogen peroxide. Ordinarily it is the aim that the anolyte in the final cell of the cascade arrangement shall have its persulfuric acid or persulfate content built up as a result of the successive electrolyses so that the concentration of percompound therein amounts to 20% or higher. It is to be understood that while both the anolyte and catholyte liquids are circulated it is the anolyte which is of value in the preparation of hydrogen peroxide although if the cell disclosed in this application should be utilized in the elec-

trolysis of other solutions it is conceivable that the catholyte might be the valuable material.

Electrolysis cells as at present employed are disclosed in the Baum Patent Nos. 1,837,177 and 1,937,621. As disclosed in these patents, the anolyte is circulated as previously described, as is the catholyte. The cathode consists of a coiled lead tube which surrounds the porous separating diaphragm and has the double function of acting 10 as a cooling coil as well as an electrical element of the cell. It will be evident from the drawing forming a part of the patents previously referred to, illustrating the electrolysis cell to which the 15 patents relate, that it is necessary for the anolyte or liquid in the anode chamber to be at a higher level than the catholyte since in the construction of this cell the anolyte is carried by an overflow pipe over into the next succeeding cell of the 20 cascade arrangement at a liquid level which is higher than the liquid level in the cathode chamber. Mere inspection of the drawings of Patents 1,837,177 and 1,937,621 will make this 25 evident as the overflow pipe, illustrated by the numeral 4 in those patents, is at a higher level than is ever attainable by the liquid within the cell container and surrounding the coiled lead 30 cathode 14. Thus, to state this fact another way, it has been customary for the porous diaphragm containing the anolyte to project out of the 35 catholyte. Therefore, in order for the anolyte liquid to flow over into the next succeeding cell it is essential in the cell illustrated in the patents referred to that the level of the anolyte within the porous diaphragm be higher than that of the catholyte in the cathode chamber.

The reason for this has been generally that of constructional expediency. Obviously it is easier to carry the overflow or discharge tube for the anolyte over the top of the cathode chamber 40 rather than carry it through the catholyte and cell wall. One important reason for this is that the cell walls are ordinarily constructed in commercial practice of glass or ceramic materials which do not readily lend themselves to the 45 piercing of apertures and the joining of metallic or non-metallic portions. Still another reason is that the anode assembly and overflow tube for the anolyte should be free to have some slight movement relative to the rest of the cell, as, for 50 example, movement occasioned by vibration. Should the glass anolyte discharge tubes be securely held, as by passing through an aperture in the cell container wall, it would be broken off in practice should the anode assembly move even 55 slightly with respect to the rest of the cell.

The necessity for operating so that the level of the anolyte is higher than the level of the catholyte has resulted in serious disadvantages. There is a tendency for the anolyte to diffuse 60 through the porous diaphragm into the catholyte, due to the pressure difference resulting from the difference in level between the two liquids. The persulfuric acid or persulfate in the anolyte which has diffused through the porous diaphragm 65 is decomposed when it comes in contact with the cathode thereby resulting in a distinct loss in yield of the product. In commercial cells it has been found that the loss of anolyte through diffusion through the porous diaphragm into the 70 cathode chamber may amount to as much as 2 cc. of solution per diaphragm per minute of operation. While the volume loss per diaphragm is approximately the same for all cells, since the difference in level between anolyte and catholyte 75 is approximately the same in all cells regardless

of their position in the cascade arrangement, the loss of persulfuric acid or persulfate will obviously increase proportionally with the concentration of the chemical in the electrolyte. As a result the anolyte flowing from cell to cell down the bank its persalt concentration increasing in its course, the loss of persulfuric acid or persulfate is appreciably greater at the bottom of each bank of cells than at the top of each bank. While the volume loss through diffusion is constant, obviously that liquid lost at the lower cells contains a greater amount of the desired per-

compound. In order to avoid diffusion of the anolyte through the porous diaphragm into the catholyte with its resulting loss in persulfuric acid or persulfate, we have improved the construction of the conventional electrolysis cell for this type of electrolysis as shown in Patents 1,837,177 and 1,937,621 thereby raising the level of the cathode 15 liquid or catholyte so that it is approximately at the same level as the anolyte. This results in an improved electrolysis cell and in an improved process of operation in which all losses of product due to diffusion through the porous diaphragms 20 are practically eliminated. While especially useful in the preparation of persulfuric acid and persulfates electrolytically, our process is of course adaptable for use in the manufacture of other chemical compounds by electrolysis. Ac- 25 cordingly with the improved process in mind, changes have been made in the conventional cell construction for the purpose of developing an improved electrolysis cell which changes are shown on the appended drawing wherein: 30

Fig. I is a plan view on the line A—A of Figs. II and III showing the electrolysis cell assembly. The porous diaphragms are shown but the anodes and other elements within the porous diaphragm constituting the anode assembly have been 40 omitted in each case. In one case the upper lip portion of the cathode box, described below, has been cut away to show the method by which the overflow tube for the anolyte is secured thereto.

Fig. II is a view partly in section and partly 45 in elevation taken on the line B—B of Fig. I.

Fig. III is a view partly in section and partly in elevation taken on the line C—C of Fig. I.

In all these views none of the construction of the anodes or anode assembly within the porous 50 diaphragm has been shown because these features are not necessary to a complete understanding of our invention. In Figs. II and III, however, that portion of the anode assembly projecting out of the porous diaphragms has been 55 illustrated. The anodes and conducting members leading thereto may be constructed as shown in the two patents previously referred to.

Referring to the drawing, the numeral 3 represents the cell container which is constructed of 60 material resistant to the action of the electrolyte or is lined with such a material. Thus lead or a resinous compound is suitable since these materials are acid resistant. The container has inserted therein a number of cylindrical porous dia- 65 phragms 4 of which six are shown. These porous diaphragms are spaced throughout the length of the cell container in line as shown in Fig. I. Surrounding the porous diaphragms and running parallel with the inner wall of the cell container 70 is a coiled tube 5 which may be of lead or of some other acid-resistant metallic material. This tube functions both as the cathode and as a means through which cooling water may be circulated for the purpose of cooling the catholyte. 75

The porous diaphragms 4, which are closed at the bottom, rest on porcelain blocks 6 which support them from the bottom of cell. From each porous diaphragm at the upper end thereof, extending over the top of the cell container 3, is a discharge spout 7 which carries the anolyte liquid from the anode chamber over to the anode chamber of the corresponding anode of the next lower electrolysis cell in the cascade arrangement. As shown, there is also a conduit 8 which conducts the catholyte out of the cathode chamber in the cell and over into the next lower cell of the cascade series (not shown). The catholyte liquid overflows flange 13 and then flows to outlet conduit 8.

Completely surrounding the coiled tube cathode both at the sides and the bottom thereof and extending the full length of the electrolysis cell, is a cathode box 9 which may be formed of lead or some other acid-resistant conducting material. This box, which may be built of sheet material functions together with the coiled tube to serve as the cathode of the electrolysis cell. The lead or other material of this cathode box is continued across the top of the cell above the coiled tube electrode and the top of the cathode box is pierced by a number of openings for various purposes as will hereinafter be apparent. It is evident that the electrolysis cell comprises a number of anodes 30 of which six are illustrated and but one cathode which functions for all the anodes.

If desired, the cell container may be omitted and the outside of the cell formed by the lead cathode box 9. However, this is generally unsatisfactory as the problem of suitably insulating the cathode boxes of adjacent cells becomes difficult to solve. We have found it best to place the cathode box within an insulating cell container as shown.

At each porous diaphragm there are openings in the top surface 10 of the cathode box through which the diaphragms and anode assemblies project. At each opening an edge or lip portion 11 is turned downwardly into the cell close up against and surrounding the porous diaphragm for a purpose which will be explained subsequently. Along the outside of all the diaphragms the lead box is formed with an upstanding lip or flange portion 13 which is bent outwardly into a series of lip portions 14 at which each anolyte overflow spout projects outwardly. These lip portions 14 are shaped to allow the tubes 7 to extend through the cathode box assembly. The overflow tubes or pipes may be cemented to the cathode box as shown at 15 and are thereby securely retained in place. As shown at 12 the upstanding lip or flange portion 13 of the cathode box is bent outwardly at one portion to form a sort of enlarged receiving spout through which the catholyte of the next higher cell in the cascade arrangement 60 flows into the cell after leaving the catholyte outlet pipe 8 of the next higher cell. While as shown in Figs. II and III, the elevation of the central part of the lip portions 14 is lower than that of the remaining portions of upstanding flange 13, this is not so in the case of the enlarged receiving spout 12. The edge or top portion of the metal forming spout 12 is at the same level as the remaining portions of the upstanding lip or flange portions 13.

If desired, the anolyte discharge tubes or spouts 7 may merely be positioned in the lip portions 14 and not securely held thereto by the cement 15. In this case the space between the lip portion 75 and the tube should be regulated so that any

catholyte liquid which may travel up between flanges 11 and anode assemblies 4 will be prevented from flowing down the outside of the discharge spout 7 by surface tension. This may be a preferable way of preventing seepage of liquid 5 down the outside of the discharge tube as we have found that some cements tend to aid the flow of catholyte out through the space between lip 14 and tube 7.

At one end of the electrolytic cell in the top portion 10 of the cathode box are provided a series of openings 16, 18, 19 and 20 as shown. Opening 16 is surrounded by a cylindrical sleeve 21 which constitutes a discharge outlet for the escape of hydrogen evolved as a result of the 15 electrolysis in the catholyte. Openings 18 and 19 constitute respectively inlets and outlets for the catholyte cooling water which circulates through the coiled cathode 5. Opening 20 provides a thermometer well wherein a thermometer may 20 be placed for the purpose of observing the temperature of the catholyte. At this time it may be mentioned that the anolyte overflow discharge tubes 7 are provided with small gas escape tubes 25 17 which permit any gases evolved in the anolyte to escape to the external atmosphere as the anolyte is carried over to the next lower cell in the cascade series.

In operation the liquid surrounding the cathode or the catholyte is maintained at a higher level 30 than previously usual at those portions of the electrolytic cell surrounding the porous diaphragms. This is accomplished by means of the elevating lips or flanges 13 attached to the cathode box 9. It is evident that the level of the catholyte 35 at each porous diaphragm may be as high as the top of the cell container 3 since the flanges 13 permit the catholyte to reach this level. Obviously then, the catholyte level is very close to the level of the anolyte which latter level is determined by the level of the discharge tubes 7. The cathode liquid can therefore fill up the space at those portions of the cell surrounding each porous diaphragm between the upstanding flange 13 and the wall of the cell container 3, thus insuring practical identity of level between the anolyte and catholyte.

The depending flange or edge portions 11 surrounding each porous diaphragm and inserted into the catholyte within the cathode box prevent 50 any hydrogen evolved within the catholyte from escaping around the porous diaphragms. Any hydrogen set free by electrolysis is thus confined within the cathode box and is allowed to escape through the discharge opening 16. It may be 55 mentioned that hydrogen is not electrically evolved in the space between the anode assembly and the depending portions 11 as the active portion of each anode (not shown) is below the level of the flanges, as illustrated in the drawings of 60 the patents previously referred to. A small amount of hydrogen may escape thru the space between flange 11 and the anode assembly 4 of each anode, but this amount is, in general, very small.

It may be mentioned that the catholyte in addition to filling up the space within the cathode box also fills up the annular chamber between the cathode box 9 and the cell container 3. When the catholyte of the next higher cell is permitted 70 to flow through discharge spout 8 over into the receiving spout 12 the catholyte obviously flows down into the interior of the cathode box through the narrow inlet space between the depending flanges 11 and porous diaphragm 4. If desired 75

an additional aperture or apertures such as illustrated at 28, 29 may be placed in the top surface 10 of the cathode box for the purpose of permitting the catholyte liquid to get down within the cathode box. Or, if desired, the receiving spout 12 may lead directly down into the interior of the cathode box. The apertures 28, 29 may be omitted if desired. If it is desired to provide positive circulation of the catholyte, the catholyte spout 8 of the cell above in the cascade arrangement may be provided with a pipe conducting the catholyte liquid directly down to the bottom of the cathode box 9. In the latter case, part of the catholyte liquid to be carried over into the next lower cell may flow upwardly through the narrow annular space between flange 11 and diaphragm 4. Of course it is to be understood that even without extending catholyte spout 8 in this manner a certain amount of catholyte circulation 20 occurs in any case.

Figs. II and III show that portion of the anode assembly which projects out of the porous diaphragms. These parts comprise principally the anolyte tube 27 which carries the anolyte from the next higher cell in the cascade arrangement into the anode chamber within the cylindrical glass member 26. Surrounding the cylindrical glass member is metallic ring 23 to which are attached tantalum strips 22 which extend down within the porous diaphragm to platinum anodes (not shown). Obviously the glass cylinder 26 provides a chamber through which cooling water may be circulated for the purpose of cooling the anolyte.

Attached to the coiled cathode and serving as a plurality of conducting members through which the electrical connections are made to the cell, is a series of metallic strips which should be formed of a metal which is resistant to the action of the catholyte. These strips are shown in Fig. I and are indicated by the numeral 25. On the drawing the electrical connection for the positive pole is indicated by a + mark, whereas the conductors electrically connected to the cathode are marked by a - sign.

One advantage obtained by our novel expedient of maintaining the level of the anolyte and catholyte liquors substantially identical is that flawed or imperfect diaphragms can be used without large losses occurring. In practice many diaphragms have small or minute apertures in them, especially after they have been in use for some time. By maintaining the levels of the two liquids substantially identical, we have made the surprising observation that intermingling of the two liquids does not occur through these apertures, as the positive pressure due to difference in level is no longer available to force one liquid into the other. This is a marked advantage of our construction and permits a considerable saving in the cost of maintaining the diaphragms, always an appreciable item in the cost of cell operation.

It will be appreciated that our improved cell may be useful for the manufacture of other substances or for other uses and accordingly we do not wish to be limited to details of construction or operation except as necessitated by the appended claims.

Therefore in the appended claims wherever we may refer to sulfuric acid solutions we mean to include therein not only aqueous solutions of sulfuric acid alone but also solutions which contain various addition agents, stabilizers, etc., from which persulfuric acid or persalts can be

obtained by anodic action. By an "electrolysis cell" is meant a cell in which electrical power is converted into chemical action as for the manufacture of desired chemical compounds.

We claim:

1. An electrolysis cell, including an anode and a cathode, said cell comprising in combination, a cell container, anolyte and catholyte liquids positioned within said cell container, and means secured to said cathode to maintain said anolyte and said catholyte liquids at approximately the same level.

2. An electrolysis cell including an anode and cathode, said cathode being formed as a coiled lead tube, said cell comprising in combination a cell container, anolyte and catholyte liquids positioned within said cell container, and means secured to and forming a part of said cathode for maintaining said anolyte and catholyte liquids at approximately the same level.

3. An electrolysis cell including an anode and a cathode, said cathode comprising a coiled lead tube, said cell comprising in combination a cell container, anolyte and catholyte liquids positioned within said cell container, a lead box positioned below the level of said anolyte surrounding said coiled lead tube cathode, and elevating flanges attached to the upper portion of said lead box to maintain said anolyte and catholyte liquids at approximately the same level.

4. An electrolysis cell formed with an anode, and a cathode in the form of a coiled lead tube, said cell comprising in combination a cell container, anolyte and catholyte liquids positioned within said cell container, a porous diaphragm surrounding an anode of said cell, a lead box positioned below the level of said anolyte surrounding said coiled tube cathode and forming therewith the cathode of said cell, an elevating flange secured to said lead box for the purpose of maintaining said catholyte at approximately the level of said anolyte liquid at those portions of the cell adjacent the porous diaphragm.

5. An electrolysis cell formed with an anode, and a cathode in the form of a coiled tube, said electrolysis cell comprising a cell container, anolyte and catholyte liquids positioned within said cell container, a porous diaphragm surrounding an anode of said electrolysis cell, a discharge tube for carrying anolyte liquid out of the electrolysis cell, a lead box positioned below the level of said anolyte surrounding said coiled lead tube cathode and forming therewith the cathode of said cell, an elevating flange adjacent the portions of said porous diaphragm and forming part of said lead box for the purpose of maintaining said catholyte liquid at approximately the same level as said anolyte liquid at those portions of the cell adjacent the porous diaphragm, said elevating flange being bent outwardly into a lipped portion at one portion thereof to provide a means through which said discharge tube may extend for the purpose of carrying the anolyte over the upper portion of the cell container.

6. An electrolysis cell formed with a plurality of anodes and a cathode, said anodes being positioned within a plurality of porous cylinders, and said cathode comprising, in part, a coiled lead tube, said electrolysis cell comprising in combination, a cell container, anolyte and catholyte liquids positioned within said container and kept separate by said porous diaphragms, a plurality of anolyte discharge tubes, a lead box surrounding said coiled tube cathode and functioning therewith as the cathode of said electrolysis cell, 75

5 said lead box being provided with elevating flanges, for the purpose of maintaining the catholyte at a level approximately equal to that of the anolyte at those portions of said electrolysis cell adjacent each of said porous diaphragms, said elevating flange being shaped at portions adjacent to each of said diaphragms so as to permit said anolyte discharge tubes to carry said anolyte over the top of said cell container, 10 and depending flanges closely adjacent to and surrounding each of said porous diaphragms for the purpose of preventing the escape of any gas which may be formed within said catholyte around said porous diaphragms.

15 7. An electrolysis cell in which the catholyte and anolyte liquids are circulated which comprises, in combination, an anode, a coiled tube cathode, conducting means surrounding said coiled cathode tube and providing a chamber 20 within which the catholyte is contained, a porous diaphragm positioned within said conducting means and surrounding said anode, the anolyte liquid being positioned within said diaphragm, means attached to said conducting means for 25 maintaining said catholyte at approximately the level of said anolyte at those portions of said electrolysis cell adjacent to said porous diaphragm, and means adjacent the porous diaphragm for preventing the escape of gases developed within 30 said catholyte at those portions of said cell adjacent said diaphragm.

35 8. In an electrolysis cell including an anode and a cathode of the type in which the anolyte and the catholyte liquids are separated by a porous diaphragm, means adjacent to said porous diaphragm for elevating the level of said catholyte so that it is substantially at the same level as said anolyte, said means being secured to and forming a part of the cathode of said cell.

40 9. An electrolysis cell comprising a cathode, a plurality of anodes, a plurality of porous diaphragms surrounding said anodes, a catholyte liquid adjacent to said cathode, a plurality of anolyte liquids positioned within said porous diaphragms and separated from said catholyte thereby, means for removing said anolyte from each of said porous diaphragms, and means adjacent to each of said porous diaphragms for elevating the level of said catholyte to approximately the level 50 of said anolytes which is determined in each case by the level of said anolyte outlet means.

45 10. An electrolysis cell comprising a plurality of anodes, a plurality of porous diaphragms surrounding said anodes, a catholyte liquid, a plurality of anolyte liquids positioned within said porous diaphragms and separated from said catholyte thereby, a cathode positioned below the level of said anolyte liquid, means for removing said anolyte from within each of said porous diaphragms, and means adjacent to each of said porous diaphragms for elevating the level of said catholyte to approximately the level of said anolyte, said level being determined by the level of said anolyte outlet means, said elevating means 60 including an elevating flange secured to and forming a part of said cathode.

65 11. An electrolysis cell which comprises an anode and a cathode, a cell container, anolyte

and catholyte liquids positioned within said cell container, a porous diaphragm surrounding said anode, said anolyte extending above the level of the major portion of said catholyte, and means for maintaining said anolyte and said catholyte liquids at approximately the same level at that portion of the cell adjacent said porous diaphragm.

12. In a two-liquid electrolysis cell including an anolyte and a catholyte, the combination which comprises a cathode positioned below the level of said anolyte liquid, an anode, a porous diaphragm separating said catholyte liquid from said anolyte liquid and means comprising an elevating flange attached to and forming a part of said cathode for maintaining said catholyte and anolyte liquids at substantially the same level at that portion of said cell adjacent said porous diaphragm.

13. A process for preparing persulfuric acid or persulfates by electrolysis which comprises treating a solution of sulfuric acid or a sulfate successively in a plurality of electrolysis cells arranged in cascade arrangement, said electrolysis cells being provided with porous diaphragms arranged to separate said electrolyte into a catholyte and anolytes positioned interiorly of said catholyte, circulating said catholyte and anolyte liquids from cell to cell in said cascade arrangement and maintaining said catholyte and said anolytes at substantially the same level in each of said electrolysis cells of said cascade arrangement throughout the entire electrolysis.

14. An electrolysis cell including anolyte and catholyte liquids, an anode and a cathode, said anode extending substantially above the level of the major portion of said catholyte liquid, and means for maintaining said anolyte and catholyte liquids at approximately the same level only at that portion of said cell adjacent said anode.

15. An electrolysis cell which comprises anolyte and catholyte liquids, an anode, a cathode positioned substantially below the level of the upper portion of said anode and means cooperating with said cathode for maintaining said anolyte and catholyte liquids at approximately the same level only at that portion of said cell adjacent said anode.

16. An electrolysis cell including an anode and a cathode, a cell container, anolyte and catholyte liquids within said cell container, the major portion of said catholyte liquid being positioned within said cell container below the upper level of said anolyte, and means cooperating with said cathode for maintaining said anolyte and said catholyte liquids at approximately the same level at that portion of said cell adjacent said anode.

17. An electrolysis cell including an anode and a cathode, anolyte and catholyte liquids, said anolyte liquid being positioned so as to have a level higher than the level of the major portion of said catholyte liquid, and means for maintaining said anolyte and catholyte liquids at approximately the same level at that portion of said cell adjacent said anode.
